(57) **CLAIM**

The ornamental design for a body of charger, as shown and described.

DESCRIPTION

FIG. 1 is a perspective view of front, right side, and top of a body of charger;

FIG. 2 is a perspective view of front, right side, and bottom thereof;

FIG. 3 is a front view thereof;

FIG. 4 is a right side view thereof;

FIG. 5 is a top plan view thereof;

FIG. 6 is a bottom plan view thereof; and

FIG. 7 is a rear view thereof;

FIG. 8 is a sectional view thereof taken along line 8-8 of FIG. 3, in which the internal components are omitted;

FIG. 9 is a reference front view showing the body of charger in use; and,

FIG. 10 is a reference right side view showing the body of charger in use.

A left side view of the body of charger is a mirror image of the right side view, and therefore omitted.

The portions of the article in broken lines are shown for illustrative purposes only and form no part of the claimed design.
